PRODUCTION OF ALCOHOLS

Karl Ziegler, Muelheim, Ruhr, Germany
No Drawing. Application July 27, 1955
Serial No. 524,798

Claims priority, application Germany August 7, 1954
17 Claims. (Cl. 260—448)

This invention relates to and has as its object, the production of alcohols from organic aluminum compounds.

In accordance with the invention, it has been found that aluminum hydrocarbons containing a methylene radical bound to the aluminum, will undergo auto-oxidation when contacted with oxygen forming aluminum alcoholates which are readily decomposed with water and/or acids into primary alcohols. Alumina in practically pure form may be recovered as a by-product of the reaction.

While it was known that certain organic metal compounds as, for example, alkyl and aryl compounds of the alkali metals, magnesium, zinc, boron, etc., would react vigorously with oxygen, the oxidation would not proceed smoothly and generally several reaction products were obtained as a result of the oxidation. Furthermore, the reaction products obtained from the oxidation of the various different compounds would vary widely from each other and it was not possible to predict or foresee how the oxidation of the organic aluminum compounds in accordance with the invention, would proceed.

The starting aluminum hydrocarbons, in accordance with the invention, may be any of the known aluminum hydrocarbons containing a methylene radical bound to the aluminum as, for example, aluminum trialkyls or aluminum alkyl hydrides. These aluminum compounds may be represented by the general formula

or

in which R and R' represent hydrogen or a hydrocarbon radical such as an alkyl radical and in which

may be in the form of a hydrocarbon ring.

These aluminum hydrocarbons may be readily and economically prepared as, for example, in accordance with the method of co-pending applications, Serial No. 484,576 filed January 27, 1955 and Serial No. 524,797 filed July 27, 1955, now Patent No. 2,835,689.

As a result of the oxidation of these aluminum hydrocarbons, aluminum alcoholates are formed which correspond in structure to the starting aluminum hydrocarbons except that an oxygen atom is interposed between the organic radical and the aluminum.

Starting aluminum hydrocarbons may also be obtained in accordance with West German Patents Nos. 917,006 and 889,229. In accordance with these German patents,

2

higher molecular trialkyl aluminum compounds are built up from triethyl aluminum by reaction with ethylene. As the alcohol ultimately produced in accordance with the invention corresponds to the organic radical portion connected to the aluminum in the starting aluminum compound, it is possible in this manner to synthesize higher primary fatty alcohols from ethylene in accordance with the invention.

In accordance with co-pending application, Serial No. 524,797 filed July 27, 1955, now Patent No. 2,835,689, an olefine is exchanged with the organic radical on an aluminum hydrocarbon thereby forming a further aluminum hydrocarbon, the hydrocarbon radical portion of which corresponds to the olefine. Thus, for example, higher boiling α -olefines may be reacted with triisobutyl aluminum to form aluminum hydrocarbons having an organic radical portion corresponding to the α -olefines. It is thus possible, in accordance with the invention, to convert olefines into the corresponding primary alcohols. Thus, for example, the α -olefines obtained from the cracking of the higher boiling fractions of the Fischer-Tropsch synthesis, may be converted into the corresponding alcohols.

Prior to the instant invention, it was not, as a rule, possible to obtain primary alcohols directly from olefines as, for example, by the addition of water. In accordance with the present invention, however, olefines may be very easily converted via the corresponding aluminum compound into primary alcohols. In this manner, in accordance with the invention, in addition to the formation of many known alcohols, it is possible to produce a very large number of completely novel alcohols which have not been previously produced nor described in the literature.

The formation of the aluminum hydrocarbon from the olefine in accordance with application Serial No. 524,797 filed July 27, 1955 which are subsequently converted into the alcohol by the oxidation and decomposition, in accordance with the invention, is merely effected by contacting an aluminum hydrocarbon having a methylene radical connected to the aluminum as, for example, triisobutyl aluminum with an olefine at a temperature between about 50 and 150° C. The olefines used for this purpose may be any olefine having a terminal double bond, cyclo olefines having 4, 5, 7 and 8 carbon atoms and at least one $\text{R}_2\text{C}=\text{CH}$ group in the ring and fulvenes.

When starting, in accordance with the invention, with aluminum hydrocarbons in which the aluminum has all its valence linkages bound to hydrocarbons, as may be represented by the formula

55 in which R is a hydrocarbon radical, during the course of the auto-oxidation, in accordance with the invention, the compounds pass successively into

and

60 The oxidation forming the first two types of compounds, takes place extremely rapidly while the oxidation forming the third type of compound requires a rather lengthy re-oxidation at ordinary or even slightly increased temperatures. It is therefore preferable to effect the auto-

oxidation initially with a gas containing only a small amount of oxygen as, for example, nitrogen to which only a small amount of air has been added and to gradually increase the oxygen concentration during the course of the reaction until finally pure oxygen is present in the final stage. The gases used for the oxidation should be extensively dried since otherwise due to side reactions, hydrocarbon radicals as such in non-oxidized form can prematurely split off the aluminum resulting in a decrease in yield. For effecting the oxidation, the oxidizing gases may be maintained in circulation and oxygen may be added at some point in the circuit.

The temperature of the oxidation may vary widely as, for example, between temperatures of minus 20 and plus 150° C. It is more practical to use temperatures between 0 and 100° C. with temperatures between about 30 and 60° C. being preferred.

In many cases, the aluminum alcoholates produced by the oxidation of the aluminum hydrocarbons, are liquids of rather low viscosity. In such cases, the auto-oxidation may be effected using undiluted starting aluminum hydrocarbons. While proceeding in such a manner, however, it is necessary to be particularly careful at the start of the reaction in determining the oxygen content of the oxidizing gas mixture. In other cases, it is advisable to effect the oxidation in the presence of solvents, as, for example, primary aliphatic or aromatic hydrocarbons.

As mentioned, the starting aluminum hydrocarbons may be in the form of monohydrides and monohydrides may be formed to a greater or lesser extent when producing the aluminum hydrocarbons have the three hydrocarbon radicals bound to the aluminum.

When oxidizing and decomposing these monohydrides, in accordance with the invention, to form alcohols, the yield is substantially less than proceeding with the aluminum hydrocarbons having three hydrocarbon radicals bound to the aluminum since in the case of the monohydrides, a maximum of two mols of alcohol can be theoretically produced per mol of monohydride. In operation, however, it is not even possible to obtain this reduced theoretical yield since the first resultant product of the oxidation is a hydroperoxide, i.e., an aluminum compound having an OOH group bound to the aluminum which contains a mobile hydrogen atom which then releases a hydrocarbon radical from the aluminum in the form of an unoxidized hydrocarbon further reducing the ultimate yield of alcohol by about one-third.

Losses of this type may be avoided by using a starting aluminum hydrocarbon which contains a minimum quantity of hydride. The formation of hydrides may be kept at a minimum when preparing the aluminum hydrocarbons, by various methods. Thus, for example, when preparing the starting aluminum hydrocarbons in accordance with U.S. patent application Serial No. 524,797 an excess of olefine may be used in the reaction and then this excess may be removed under as gentle conditions as possible at the lowest possible temperature, or the first oxidation in accordance with the invention may be effected in the presence of this excess olefine and the olefine may be subsequently separated from the formed aluminum alcoholate by distillation.

It is often desirable, particularly when using more expensive olefines to completely convert these olefines into the alcohols via the alcoholate without the use of an excess. In such cases, the olefines may be converted into the corresponding aluminum hydrocarbons using an excess of the initial aluminum hydrocarbon which is reacted with the olefine as, for example, triisobutyl aluminum. Under these conditions, however, monohydrides are formed since the triisobutyl aluminum readily loses an isobutyl radical while hot forming diisobutyl aluminum monohydride. After treatment of the olefine with the triisobutyl aluminum, it is therefore advisable to again treat the reaction product prior to the oxidation in accordance with the invention, with a less expensive

olefine which may, for example, be isobutylene, at the lowest possible temperature in order to convert all the Al—H bonds present in the reaction mixture into Al—R bonds and, in particular, when using isobutylene to isobutyl radicals. As side products there is then produced upon the oxidation-decomposition, in accordance with the invention, a certain quantity of isobutyl alcohol. On the other hand, however, the conversion of the olefine employed corresponding to the desired reaction product into the alcohol takes place substantially more easily than if this after-treatment were omitted and if quantities of aluminum monohydrides were present.

It is of particular advantage that the oxidation, in accordance with the invention, may be effected in the presence of inert hydrocarbons. It is thus possible when converting the olefines ultimately to be converted to alcohols, in accordance with the invention, into the starting aluminum hydrocarbons, to use hydrocarbon mixtures which consist only in part of these olefines. The aluminum hydrocarbons formed will therefore be formed in admixture with these inert hydrocarbons. Accordingly, the oxidation in accordance with the invention, is effected using this entire mixture and after the oxidation, the formed aluminum alcoholates may easily be separated from the other hydrocarbons by distillation, possibly under vacuum. The aluminum alcoholates are generally difficulty volatile and remain as the distillation residue. This distillation residue which is substantially free from the other hydrocarbons, may then be directly converted into the desired alcohols, free of the hydrocarbons with water and/or acids. This obtaining of the hydrocarbon-free alcohol in a simple manner is a substantial advantage as compared with the known methods for the conversion of olefines into oxygen-containing compounds as, for example, in accordance with the so-called oxo-synthesis. As is well known, hydrocarbon mixtures may not be used in the oxo process if pure reaction products are desired since it is not possible to separate the aldehydes formed in the oxo process from the hydrocarbons with the same boiling point by distillation alone.

The following examples are given by way of illustration and not limitation:

Example 1

Nitrogen was blown through 366 grams tri-n-octyl aluminum prepared by the process of patent application, Serial No. 524,797 and triisobutyl aluminum in a recycle apparatus. Oxygen was carefully added to the circuit in such a manner that the oxygen content in the circulating gas was about 5%. The aluminum tri-n-octyl warmed up and the reaction vessel used was cooled from the outside. As the heat given off in the reaction vessel became smaller, the oxygen content in the circulating stream was increased first of all to 10 to 20% and finally pure oxygen was employed. The oxidation required 3 to 8 hours depending on the intensity of the cooling. Towards the end, the absorption of oxygen slowed down greatly. The apparatus was so arranged that the oxygen absorption was under control and the operation discontinued when no more oxygen had been absorbed for at least one-half hour to one hour. The gases used were very carefully dried by a good drying agent, for example, potassium hydroxide heated to 400° C., dried and applied to pumice stone or magnesium perchlorate. During the oxidation, the aluminum trioctyl which initially had a thin liquid consistency became viscous, but the reaction could be carried out without difficulty. The thick, oily aluminum octylate finally obtained was decomposed by the addition of water with heating. Thereupon the octyl alcohol formed was distilled over by steam distillation. The oil which passed over with the distillate was separated and dried over potassium carbonate. Distillation, preferably in a vacuum, was then effected. There were obtained 320 to 350 grams of the primary normal octyl alcohol,

having an entirely constant boiling point of 81.5°/8 mm. and of excellent odor.

As residue of the steam distillation, there were obtained an aluminum hydroxide paste from which the aluminum hydroxide could easily be separated in the known manner by filtration or centrifuging, and can thereupon be converted by the removal of water into an alumina of very high purity.

Example 2

A solution of tri phenyl-ethyl aluminum in hexane is first of all prepared in accordance with Example 3 of patent application Serial No. 524,797 and then oxidized in the manner described in Example 1. The treatment carried out in the manner indicated in Example 1 results in the formation of phenylethyl alcohol

of a boiling point of 98–101° C./8 mm. or 220° at ordinary pressure, which corresponds to the value given in the literature. The yield is about 70% of the theoretical quantity.

Example 3

To 10 kgs. of a product obtained by the cracking of higher Fischer-Tropsch paraffins and having a boiling point of 180–230° C. with an olefine content determined by bromine titration of 8 moles of olefine per kilogram and an α -olefine content determined spectroscopically in infrared light of 5.8 moles per kilogram, there were added 3 kilograms aluminum triisobutyl. The mixture was thereupon converted, in accordance with Example 5 of patent application Serial No. 524,797 at 120–130° C. in vacuum into the aluminum compound. The solution of the aluminum hydrocarbons formed in the inert accompanying substances of the α -olefines was then transferred into a high cylindrical iron vessel provided on the outside with water cooling and thereupon very thoroughly dried air was blown through, first of all cautiously, and thereupon continuously more intensively. The cooling of the reaction mixture and the gas velocity were so regulated that the temperature as far as possible did not exceed +30° C. Finally, the temperature was increased to 50° C. and oxidation was continued for about 2 hours with pure oxygen. The solution obtained in this manner of the aluminum compounds of the alcohols produced was thereupon transferred into a distilling vessel and freed as completely as possible from the hydrocarbons by heating under vacuum. If importance is placed on the absolute freedom of the alcohols to be obtained from hydrocarbons, after the hydrocarbons have been driven off, superheated vapors of a hydrocarbon of relatively low boiling point, for instance, benzene, can be blown through the liquid aluminum alcoholate remaining in the residue, whereupon the last traces of higher hydrocarbons still adhering to the liquid aluminum alcoholate will be driven off, or a very effective continuously operating thin-layer vacuum evaporator may be used to drive off the hydrocarbons.

In each case, there is obtained the oily alcoholate which is then advisedly further treated by decomposition with water in accordance with Example 1. The higher boiling fractions of the alcohols obtained are finally separated from the aluminum hydroxide paste by distillation with superheated steam under a vacuum. The aluminum hydroxide paste can be very readily converted back into pure alumina by calcining. The entire organic portions of the distillate are collected.

The quantity of crude alcohols to be obtained depends somewhat on the initial olefines employed. In one special case, there were obtained, for example, 6 kilograms of crude alcohol which could be further split up by fractional vacuum distillation. The individual fractions to be obtained in this connection depend, of course, on the sharpness of the hydrocarbon cut introduced. With an introduced fraction of a boiling point of 180–

230° C., there were regularly still present small portions of C_8 -olefines so that the first alcohol obtained upon distillation in an effective column in vacuum, is customarily the primary octyl alcohol. By further distillation on an effective column, there can be obtained one after the other all primary straight-chain fatty alcohols having 9 to 16 carbon atoms, with which however, if a hydrocarbon prepared by Fischer-Tropsch synthesis is initially used, there are also admixed certain quantities of methyl-branched fatty alcohols. The pure primary fatty alcohols, particularly the higher members having 12 or more carbon atoms, can readily be caused to crystallize from the corresponding fractions by cooling and then removed by suction filtering or centrifuging.

Example 4

The oxidation of a higher alkyl aluminum which can be obtained by heating 114 grams aluminum triethyl plus 420 grams ethylene in an autoclave at 100 to 110° C. until the disappearance of the ethylene pressure, takes place in a very similar manner. As solvent, toluene is used (twice the volume of the alkyl aluminum compounds). The treatment carried out in the manner indicated in Example 3 gives the entire series of primary normal fatty alcohols starting at n-hexyl-alcohol up to alcohols with 18 to 20 carbon atoms with a maximum of n-dodecylalcohol.

Example 5

118 grams of the aluminum compound obtained from 1-vinylcyclohexene-(3) were diluted with 200 cc. octane and subjected to oxidation in accordance with Example 1. Upon working-up there is obtained tetrahydrophenyl-alcohol of the following formula:

35

40

45

This alcohol is a colorless oil of a boiling point of 105 to 107° C./15 mm.; $n_{D}^{20}=1.4831$. From limonene and camphene there can be obtained in a simple manner the alcohol having the formulas

50

and

55

respectively.

Example 6

336 grams "dimeric dodecene" (prepared in accordance with the process of West German Patent 878,560) is first of all converted by the method of Example 7 of patent application Serial No. 524,797, filed July 27, 1955, with aluminumtriisobutyl into the aluminum compound

which is then oxidized with 600 cc. of toluene, diluted in the manner described in the other examples, and there are obtained 300 gm. of the alcohol

The alcohol is a colorless oil of a boiling point of 164-166° C. at 10⁻⁴ mm.

I claim:

1. Process for the production of primary alcohols which comprises contacting with oxygen an aluminum hydrocarbon having a

radical bound to the aluminum in methylene linkage therewith, at a temperature between -20° and 150° C. thereafter decomposing the aluminum alcoholate formed with a member selected from the group consisting of water and acid, and recovering the primary alcohol formed.

2. Process according to claim 1, in which said contacting is effected in the presence of a solvent.

3. Process according to claim 2, in which said solvent is a member selected from the group consisting of aliphatic and aromatic hydrocarbons.

4. Process according to claim 1, in which said contacting with oxygen is effected by contacting the aluminum hydrocarbon with a gas having a low oxygen content, and increasing the oxygen content of the gas during said contacting until the gas has a high oxygen content.

5. Process according to claim 1, in which said contacting is effected at a temperature between about -20 to +150° C.

6. Process according to claim 1, in which said contacting is effected at a temperature between about 0 and 100° C.

7. Process according to claim 1, in which said contacting is effected at a temperature at 30 to 60° C.

8. Process according to claim 1, in which an aluminum hydrocarbon is substantially free from aluminum hydride.

9. Process according to claim 1, in which said aluminum hydrocarbon contains aluminum hydride and which includes contacting the aluminum hydrocarbon with an olefine prior to said contacting with oxygen.

10. Process according to claim 9, in which said olefine is isobutylene.

11. Process according to claim 1, in which said aluminum hydrocarbon is in admixture with hydrocarbons and which includes after said contacting with oxygen, distilling off the hydrocarbons from the formed aluminum alcoholate prior to said decomposition.

12. Process for the production of aluminum alcoholates which comprises contacting with oxygen an aluminum hydrocarbon having a

radical bound to the aluminum in methylene linkage therewith at a temperature between about -20 to +150° C., and recovering the aluminum alcoholate formed.

13. Process according to claim 12, in which said contacting is effected with a gas mixture containing a low oxygen content, and in which the oxygen content of the gas mixture is increased during said contacting until the gas mixture has a high oxygen content.

14. Process for the production of primary alcohols from olefines which comprises contacting an aluminum hydrocarbon with an olefine having a terminal double bond, at a temperature between about 50 and 150° C., thereafter contacting the aluminum hydrocarbon formed by displacement of the initial hydrocarbon radical with a hydrocarbon radical corresponding to the olefine with oxygen at a temperature between about -20 and +150° C., decomposing the aluminum alcoholate formed with a member selected from the group consisting of water and acid, and recovering the primary alcohol formed.

15. Process according to claim 14, in which said starting aluminum hydrocarbon is triisobutyl aluminum and in which said olefine is an olefine other than isobutylene.

16. Process according to claim 14, in which said olefine is present in admixture with other hydrocarbons and which includes distilling off the hydrocarbons from the formed aluminum alcoholate prior to said decomposition.

17. A process for the production of primary alcohols having the general formula ROH which comprises contacting with molecular oxygen under anhydrous conditions an aluminum trialkyl compound having the general formula AlR₃, wherein R is an alkyl group containing at least two carbon atoms having a

radical bound to the aluminum in methylene linkage therewith, at an oxidizing reaction temperature maintained at less than about 150° C. and hydrolyzing the aluminum trialkoxides formed and recovering the primary alcohols thus produced.
